APPARATUS FOR FORGING CRANK-SHAFTS AND LIKE WORK-PIECES

George Shewan-Cleghorn, Sheffield, England, assignor of one-half to English Steel Corporation Limited, Sheffield, England, and one-half to Compagnie des Forges & Acieries de la Marine & de St. Etienne, Paris, France

Application June 23, 1953, Serial No. 363,576

Claims priority, application Great Britain July 24, 1952

3 Claims. (Cl. 29—6)

This invention relates to an improvement in apparatus for forging crank-shafts and like work-pieces of the kind described in prior United States specification No. 2,534,613.

In the aforesaid prior specification, there is disclosed an apparatus, which can be utilised in conjunction with an ordinary forging press, for the purpose of forging crank-shafts and other work-pieces having enlarged parts separated by eccentric or concentric constructions. Such work-pieces are forged from blanks provided with swells separated by constrictions or from blanks of plane, cylindrical or other shape depending upon the final shape to be obtained, the intercalary parts of the blanks, i.e., parts which do not have to undergo considerable deformation during the forging operation, having shapes and dimensions to allow their accommodation in dies suitably recessed for the purpose. The apparatus for carrying out the forging operation is constituted by end dies which receive the extremities of the blank and by two central half dies which act transversely for the displacement of the middle intercalary part of the blank, the end dies having their movements related to those of the central die by means of ramps in such a way that the end dies ensure the upsetting or longitudinal forging of the blank while the central die displaces the middle intercalary part.

In the aforesaid apparatus the movements of the central die are co-ordinated with the respective end dies by separate ramp means each of which includes inclined co-operating surfaces. In order to ensure even distribution of load on each end die it is therefore essential that the ramps are machined and fitted with great accuracy. In addition, the rubbing friction which necessarily occurs between the ramp surfaces not only causes wear necessitating frequent renewal of these surfaces, but also absorbs an appreciable amount of the power of the apparatus which could otherwise usefully be employed in the forging operation.

A main object of the present invention is to avoid the foregoing disadvantages in a manner which increases the efficiency of the apparatus whilst at the same time simplifying and reducing the cost of manufacture.

According to the present invention, there is provided an apparatus of the kind specified wherein movement of the central die during a working stroke is transmitted to the end dies by link means which are adapted and arranged to exert an increasing pressure on said end dies towards the end of the working stroke.

According to a more limited aspect of the invention there is provided an apparatus for forging crank-shafts and like work-pieces from blanks, comprising end dies adapted to receive the extremities of a blank and acting to effect the upsetting or longitudinal forging of the said blank and two central half dies acting transversely for the displacement of a middle intercalary part of the blank which does not have to undergo any considerable deformation during the forging operation, the said cen-

2

tral half dies being actuated by a reciprocable crosshead of the apparatus and the said end dies having their movements related to those of the central die by means of links which are adapted and arranged to exert an increasing pressure on said end dies towards the end of the working stroke of the crosshead.

In order that the invention may be clearly understood and readily carried into effect, one embodiment thereof will now be described in detail with reference to the accompanying partially diagrammatic drawings from which parts of known construction having no direct bearing on the present invention have been omitted for the sake of clarity. In the drawings,

Figure 1 is a broken section partly along the longitudinal central axis of the apparatus and partly along the line B—B of Figure 2, and

Figure 2 is an end elevation of the apparatus partially in section on the line A—A of Figure 1 and partially in section on the line D—D of Figure 1.

The apparatus as illustrated has a base or bed 1 the upper surface of which is shaped to provide sideways 2 on which can slide two cradles 3. Also mounted on the bed 1, approximately centrally, is the lower half of a centre die shown diagrammatically at 4a. This lower half die is carried by a hydraulic piston and cylinder assembly which is again shown diagrammatically at 5. Push back hydraulic pistons are also provided, in known manner, in the bed for returning the half die 4a to its starting position after a forging operation, but these pistons form no part of the present invention and are not shown in the drawings. Two lateral hydraulic push-back pistons 6 are associated with each cradle 3 for the purpose of returning the latter to their starting positions after a forging operation, these pistons 6 operating in cylinders 6a formed in the bed 1 and being coupled to the respective cradles by bracket plates 7.

The sliding cradles 3 each carry an end die having an upper part 8 and a separate lower part 8a. When forging a crank-shaft for example, these end dies serve to receive respectively the parts of the blank situated on either side of that which is to form the crank-throw. The parts 8, 8a of the end dies are separable by means of hydraulic push-back pistons 9 operating in cylinders 9a in a reciprocable crosshead 10 of the apparatus, there being two such pistons 9 associated with the upper half 8 of each end die. For the purpose of clamping the end die parts together, with portions of a blank gripped therebetween, there are provided two hydraulic pistons 11 operating in cylinders 11a in the crosshead 10, there being one such piston 11 associated with each upper part 8 of an end die. The pistons 11a are connected with the respective upper parts of the end dies by means of a slide block 11b on each piston which engages a slideway 8b on the top of the associated end die part 8.

The crosshead 10 also carries, approximately centrally, the upper part of the centre die shown diagrammatically at 4b.

For the purpose of co-ordinating the movement of the end die cradles 3 with the centre die 4a, 4b, during lowering of the crosshead 10, there are provided pairs of parallel link arms 12 between the crosshead and each end die cradle 3. Two pairs of link arms 12 are associated with each end die cradle, one such pair being located on either side of the supported end die. The link arms 12 are hingedly secured at their upper ends to hinge pins 13 mounted in bearings in the crosshead 10. Four such pins 13 may be provided, as shown, extending across the crosshead 10 in parallel relationship, each pin 13 carrying one link arm 12 from each of the two pairs of link arms associated with the underlying cradle 3. Alternatively, eight hinge pins may be appropriately mounted

in the crosshead, each pin carrying a single link arm. The hinge pins 13 extend transversely to the path of movement of the end dies and, extending parallel to these pins 13, are bearing pins 14 which are secured to the respective cradles 3. These bearing pins 14 are located so that each pin 14 has the lower end 12a of a link arm bearing thereon. The pins 14 are arranged to pivot in relation to the cradles 3 by which they are carried and, to facilitate engagement with the lower ends 12a of the respective link arms, these latter arm ends are formed with a V-shaped groove and the seating surface of each bearing pin 14 is formed with a corresponding V-section.

The location of the hinge and bearing pins 13 and 14 and the length of the link arms 12 is such that the link arms all incline inwardly from their upper ends towards the central die 4a, 4b. The link arms 12 of each pair of links thus constitute two sides of a parallelogram which is completed by parallel lines passing through the pivotal axes of the associated hinge and bearing pins. Each cradle 3 is thus controlled by two such linkage parallelograms which operate in planes parallel to each other.

The zero or free position of the link arms 12 is determined by suitable stops 15 which, in this example, are integral with the crosshead 10. If desired, however, the stops 15 could be made adjustable. As an example, the link arms 12 of each pair may be inclined inwardly from their upper ends at some 40-45° to the horizontal when the associated end dies and cradles are fully withdrawn as shown in Figure 1.

In operation, when the forging press is set in motion to lower the crosshead 10 and operate the central die 4a, 4b, the link pairs serve to press the cradles 3 and end dies 8, 8b carried thereon inwardly in synchronism with the movement of the crosshead 10. As the crosshead moves further down on its working stroke and the link arms 12 press the associated cradles further along their sideways 2 towards the central die 4a, 4b, the angular position of the individual link arms 12 approaches closer to the horizontal whereby an increasing horizontal force component is obtained as the working stroke proceeds. This horizontal force component will, of course, reach its maximum towards the end of the working stroke which is just when the maximum upsetting effect on the blank being forged is required.

I claim:

1. In an apparatus for forging crank-shafts from blanks in which a transversely acting central die actuated by a reciprocable cross head operates in synchronism with movable end dies which approach one another in the

direction of the longitudinal blank axis, the provision of motion transmitting means between said cross head and end dies comprising at least two pivotal thrust arm mountings located on said cross head one on each side of the central die, thrust arms which depend respectively from said mountings at an inward inclination towards said central die, stop means on said cross head for determining the angular positions of rest occupied by said thrust arms when the cross head is withdrawn and pivotal seatings on the respective end dies positioned to receive the lower arm ends when the cross head is carrying out downward working stroke and the end dies are in the withdrawn position, the arrangement being such that said end dies will be caused by said thrust arms to approach one another under an increasing force component as the working stroke proceeds.

2. Motion transmitting means as claimed in claim 1 in which four thrust arms are associated with each said end die, said four arms being arranged in pairs with the arms of each said pair constituting two opposite sides of a parallelogram linkage which is completed by parallel lines passing respectively through the centres of pivotal mountings of the pair of arms and through the centres of the pivotal seatings of said pair of arms and in which the lower end of each arm is formed with a V-shaped seating recess and the seatings for the lower arm ends are in the form of laterally projecting pivotally mounted pins each having a seating surface formed with a corresponding V-section.

3. Motion transmitting means as claimed in claim 2 including adjustable stops on said cross head for determining the angular position of rest of said thrust arms when said cross head is raised whereby said thrust arms will automatically engage their respective seatings associated with the end dies when the cross head is lowered on a working stroke from the starting position of the apparatus.
